US0D1041458S

(12) **United States Design Patent** (10) **Patent No.:** **US D1,041,458 S**
(45) **Date of Patent:** **** Sep. 10, 2024**

(54) **HEADPHONE HOLDER**

(71) Applicant: **Shenzhen Zhiyoumei Technology Co., Ltd**, Shenzhen (CN)

(72) Inventor: **Wenjing Hu**, Shenzhen (CN)

(73) Assignee: **Shenzhen Zhiyoumei Technology Co., Ltd**, Shenzhen (CN)

(**) Term: **15 Years**

(21) Appl. No.: **29/948,697**

(22) Filed: **Jun. 21, 2024**

(51) LOC (14) Cl. **14-01**

(52) U.S. Cl.

USPC **D14/224**

(57) **CLAIM**

The ornamental design for a headphone holder, as shown and described.

DESCRIPTION

FIG. 1 is a front perspective view of a headphone holder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view thereof, in a closed position.

1 Claim, 9 Drawing Sheets
